UNITED STATES PATENT OFFICE.

HANS USENER, OF KIEL, GERMANY.

ARMATURE FOR DISTANT-CONTROL INDICATORS FOR CONTINUOUS AND ALTERNATING CURRENT.

Application filed April 28, 1923, Serial No. 635,395, and in Germany December 16, 1922.

The present invention relates to a novel form of armature in electromagnetic machinery, especially adapted for use in arrangements for transmitting signals by the 5 different angular portions of the armature at a transmitting station which cooperates with a similar armature at the receiving station. Transmitting systems of this character are well known in the art.

10 The particular improvement here involved relates to certain constructional forms of the armature by which certain advantages, hereinafter pointed out, are gained.

In signalling systems of the above character it is frequently required that the armature of the electromagnetic transmitter and receiver assume a great many different angular positions, in order to transmit a large 15 number of signals represented by these different positions. Also frequently a great 20 number of such individual transmitters or receivers are mounted side by side.

The former requirements necessitates great 25 sensitiveness of the armature to changes in current so that for instance the armature of the receiver will readily follow even slight angular movements of the transmitter armature. This sensitiveness has heretofore been obtained by very liberally dimensioning the 30 size of these armatures.

The second mentioned requirement necessitates the dimensioning of the armature sizes very small so as to save room on the instrument panels.

35 The present novel construction reconciles these two contrary expedients and permits the use of armatures of comparatively small size which at the same time are responsive to even small angular displacements between 40 the transmitter and receiver.

A constructional form of the invention is illustrated in the drawing which represents the device in longitudinal section.

Referring to the drawing 1 is an armature 45 shaft which is journaled at 2 in the cover 17 of the indicator casing 18. The inner end of the shaft is journaled in a step bearing 5 provided at the inner end of an adjustment screw 4 secured in the apparatus in the following manner. A stationary iron core 9 is 50 arranged in the casing between the two poles 14 of the indicator system, this core being provided with a rearwardly extending sleeve 8 threaded into the rear wall 19 of the casing and secured by means of a lock nut 3.

The aforementioned screw 4 is threaded into this sleeve and the shaft bearing end as shown consists of a finely polished point 6 and a small distance away from this point a collar 7 is provided. By thus arranging the 60 journalling of the inner end of shaft 1 it may be very exactly adjusted against undue longitudinal motion and it is journalled with very little friction since when the apparatus is used in up-right position the end 6 of the 65 shaft serves as a step bearing and when the apparatus is used in horizontal position the collar 7 which of course if also finely polished serves as a bearing.

Shaft 1 is provided with a long threaded 70 portion onto which is threaded a hub 10 which carries a shell 11 which completely surrounds stationary core 9 including the greater portion of the sleeve 8 of that core. This shell is composed of metal in case direct 75 current is employed and of a suitable insulating material in case alternating current is employed. This shell 11 carries the armature winding 12 and it may be properly adjusted in the magnetic field produced by 80 poles 14, and so that it clears the fixed iron core 9 uniformly on all sides, by means of adjusting the threaded hub 10 on shaft 1. By this novel arrangement the weight of the 85 armature itself is materially reduced, carrying no heavy core so that it becomes very sensitive to even light torques exerted by any field induced thru currents flowing in the armature so that this armature may be held within comparatively small dimensions. 90

At the same time by the particular core construction the core is not supported in any way from the armature or its shaft at the bearings of the latter and thus the weight 95 of the heavy core hinders in no way by friction the free movement of the armature which would otherwise occur if the core were centrally supported at its free inner end of the armature shaft as is the practice in the art at present. Furthermore the shaft 1, 100 only carrying the light weight of the armature, is journaled by this novel arrangement at its inner end very near the center of gravity of the armature and thus the weight 105 of the armature becomes effective at the end of the shaft which is particularly delicately journaled and in which frictional losses thus become least effective. Thus the bearing at the outer end 2 of the shaft only becomes a guiding bearing rather than a bear- 110

ing which carries a substantial portion of the armature weight. The end of the shaft protruding beyond the casing cover 17 is provided with a square portion as shown at 5 16 on which a hand may be mounted and which is held in place by the nut 15.

By this novel arrangement the weight of the armature itself is materially reduced so that it becomes very sensitive to even slight 10 torques exerted by any field induced through currents flowing in the armature, so that the armature may be held within comparatively small dimensions. At the same time, by the 15 particular core construction, the core does not receive any support from the armature at the bearings of the latter and thus the weight of the heavy core does in no way hinder by friction the free movement of the armature, which otherwise would occur if 20 the core were centrally supported at its free inner end on the armature shaft as is the practice in the art at present.

I claim:—

1. An electromagnetic indicator of the 25 character described having fixed field poles, an iron core disposed between said poles and having a sleeve extending from one of its ends, means for holding said sleeve fixed at its free end to maintain said core in fixed 30 position between said poles, and an armature winding disposed between said poles and completely surrounding said core and means journaled in said sleeve for rotatably supporting said winding to permit it to 35 freely rotate around said core.

2. An electromagnetic indicator of the 40 character described having fixed field poles, an iron core disposed between said poles and having a sleeve extending from one of its ends, means for holding said sleeve fixed at 45 its free end to maintain said core in fixed position between said poles, a longitudinally adjustable step bearing extending into said sleeve, an indicator shaft extending into said core from the unsupported end of the latter and being journaled in said step bearing, means for journalling the outer end of said shaft, and an armature winding disposed

between said poles and completely surrounding 50 said core, means for freely supporting said armature, said supporting means being mounted on said shaft near its step bearing end to permit the armature to freely rotate around said core.

3. An electromagnetic indicator of the 55 character described having fixed field poles, an iron core disposed between said poles and having a sleeve extending from one of its ends, means for holding said sleeve fixed at 60 its free end to maintain said core in fixed position between said poles, a longitudinally adjustable step bearing extending into said sleeve, an indicator shaft extending into said core from the unsupported end of the latter and being journaled in said step bearing, means for journalling the outer end of said 65 shaft, and a shell carrying an armature winding and being disposed between said poles, said shell completely surrounding said core and means for adjustably fixing said 70 shell to said shaft near its step bearing end to permit the shell to freely rotate around said core.

4. An electromagnetic indicator of the 75 character described having a casing and fixed field poles mounted in said casing, an iron core disposed between said poles and having a sleeve extending from one of its ends, said sleeve being fixed at its free end 80 to said casing thereby serving as a sole support for said core, a longitudinally adjustable step bearing extending into and being mounted in said sleeve, an indicator shaft extending into said core from the unsupported end of the latter and being journaled in said step bearing, the outer end 85 of said shaft being journaled in said casing, and a shell carrying an armature winding and being disposed between said poles, said shell completely surrounding said core and means for adjustably fixing said shell 90 to said shaft near its step bearing end to permit the shell to freely rotate around said core.

HANS USENER.
